[57] CLAIM

The ornamental design for a combined handlebar mounted can holder and lid, as shown and described.

DESCRIPTION

FIG. 1 is a perspective view of a combined handlebar mounted can holder and lid showing our new design; FIG. 2 is a side elevational view thereof taken from one side, the opposite side appearing as substantially a mirror image;

FIG. 3 is a front elevational view thereof;

FIG. 4 is a rear elevational view thereof;

FIG. 5 is a top plan view thereof; and

FIG. 6 is a bottom plan view thereof.

*Fig. 1.**Fig. 2.**Fig. 3.**Fig. 4.**Fig. 5.**Fig. 6.*
